CLAIM

The ornamental design for a combined lifting tool and mounted yoke for handicapped person, as shown and described.

DESCRIPTION

FIG. 1 is a rear perspective view of a combined lifting tool and mounted yoke for handicapped persons, showing my new design;

FIG. 2 is a perspective view of the tool portion thereof;
FIG. 3 is a rear perspective view of the yoke portion thereof;

FIG. 4 is a front perspective view of the yoke portion thereof, and

FIG. 5 is a rear perspective view showing a handicapped person within the yoke portion thereof. The broken line showing of the handicapped person is for illustrative purposes only and forms no part of the claimed design.

Portions of the yoke and lifting tool have been omitted in FIGS. 2-5 for clarity of illustration only.
